MILLER REESE HUTCHISON, OF LLEWELYN PARK, WEST ORANGE, NEW JERSEY, AS
SIGNOR, BY MESNE ASSIGNMENTS, TO ACOUSTIC PRODUCTS COMPANY, OF NEW
YORK, N. Y., A CORPORATION OF DELAWARE

CLOSED-END RESONATING HORN

Application filed May 24, 1927. Serial No. 193,812.

This invention relates to sound generating devices, and, more particularly, to sound reproducers in which a column of air is set into vibration by a mechanical diaphragm.

In order to secure an accurate and undistorted reproduction of the various notes comprising a chromatic scale, it is desirable to provide a plurality of resonating chambers which may be operated in conjunction with the reproducing means, such as an electromagnetic unit having a vibrating diaphragm, which serves to selectively amplify certain of the notes impressed thereon. Each of the resonating chambers may be tuned to a definite note of the chromatic scale and utilized for reproducing that particular note or various overtones or harmonics thereof. It is thus necessary to employ only twelve chambers resonant to the various notes in one octave of the chromatic scale in order to amplify and reproduce the entire range of musical frequencies.

Should an open end resonator be employed, the length thereof would be excessive due to the fact that such a device is resonant to a wave having a length only twice that of the pipe itself. This would be particularly noticeable if the device is made resonant to one of the lower octaves and will cause the arrangement to be unsuitable for private use where only a small space is available.

I accordingly utilize a resonating chamber formed by a pipe having a closed end for amplifying the waves produced by a vibrating diaphragm. Since such a pipe is resonant to a wave four times its own length it occupies only half the space required by an open end pipe which is resonant to the same note. A bank of twelve closed end pipes, each tuned to a definite note in the chromatic scale, and energized by a suitable diaphragm, may consequently be employed for the reproduction of the various notes comprising a complete scale.

In accordance with this invention, a pipe having a closed end is utilized as a resonator associated with the diaphragm of an electromagnetic unit. The diaphragm is analogous to a tuning fork and sets up waves of compressions and rarefactions in the pipe, which, if

they are of the frequency to which the pipe is resonant, are amplified and impressed upon the surrounding medium. Twelve such resonators are employed which are tuned respectively to the several notes comprising an octave in the chromatic scale. Since the devices are capable of amplifying the various overtones of their fundamental frequency but are relatively incapable of reproducing notes of lower frequencies, it is usually preferable to tune the resonators to the lowest octave it is desirable to reproduce. Their fundamental frequency and the various overtones will then comprise the complete musical scale, and any notes of lower frequency which may be present will be largely suppressed.

The invention also consists in certain new and original features of construction and combinations of parts hereinafter set forth and claimed.

Although the novel features which are believed to be characteristic of this invention will be specifically pointed out in the claims appended hereto, the invention itself, as to its objects and advantages, the mode of its operation and the manner of its organization, may be better understood by referring to the following description taken in connection with the accompanying drawing forming a part thereof, in which like reference characters have been used to denote like parts in the various figures. Since such illustration is, however, primarily for purposes of disclosure, it will be understood that the structure and the method of operation thereof may be modified in various respects without departing from the broad spirit and scope of the invention.

One embodiment of the invention has been shown for purposes of illustration in the accompanying drawing, in which

Fig. 1 illustrates a closed end resonator constructed in accordance with this invention;

Fig. 2 is a front elevation of a bank of such resonators, and

Fig. 3 shows a modification thereof in which the vibrating diaphragm is located at one end of the pipe.

In the following description and in the claims the various parts of the apparatus and

details of the invention will be identified by specific names for convenience, but they are intended to be as generic in their application as the art will permit.

6 Referring to the drawing more in detail, and in particular to Fig. 1, the pipe 1 is shown having one end closed and the other end T-shaped. Electromagnetic reproducing unit 2, which may be of any well known form 10 having movable diaphragm 3, is secured to one side of the T-shaped end, and the opposite side thereof may be provided with a bell or horn 4. Vibrations of the diaphragm in response to applied pulsating electric currents cause compressions and rarefactions 15 in the air within the tube, which travel outwardly as sound waves. If the waves are of a frequency to which the pipe is resonant they will set up vibrations within the pipe 20 and be re-enforced thereby for producing a strong musical note.

Fig. 2 illustrates a plurality of pipes 1 and co-operating electromagnetic units 2 for imparting sound waves thereto. Pipes 1 are 25 of different lengths and are tuned to different frequencies. Preferably a bank of twelve such units should be employed each unit being tuned to a different note in the chromatic scale as will be hereinafter explained.

30 In the modification shown in Fig. 3, the various elements are similar to those disclosed in Fig. 1, and are given the same reference numerals. The electromagnetic unit 2, however, is located across the end of pipe 1 35 instead of at the side thereof. In this case, the diaphragm is located directly over the air column and bell 4 is mounted at right angles thereto.

In the operation of the above described device, 40 waves of a length four times that of the air column in tube 1 will be most strongly re-enforced and amplified. Operation is in this respect similar to that of a tuning fork which is spaced above a closed air column and produces air waves comprising rarefactions and compressions which are reflected by the closed end of the column, and re-enforced. The action of resonator is selective 45 as to waves of its own fundamental frequency and overtones or harmonics thereof. Waves 50 of other frequencies and particularly those of a frequency lower than a fundamental are re-enforced but slightly, consequently in the resulting note emitted the ratio of the 55 amplitude of the waves of desired frequency to those of other frequencies is considerably increased.

A bank of such resonators is preferably 60 employed each individual unit being tuned to a definite note of the chromatic scale comprising a predetermined octave. If the selected octave is the lowest which it is desired to reproduce, the device will amplify 65 notes over the entire musical range and suppress other noises.

The invention therefore provides a means for efficiently producing sound waves corresponding to musical notes and for emitting such waves with a minimum amount of distortion and interference. The device is furthermore constructed to occupy a minimum amount of space. As a result, the entire chromatic scale, with its overtones and harmonics, may be reproduced by an instrument having theoretical as well as practical 70 purity of tone from a small and compact unit which may be installed in a single appropriate cabinet and can be installed at any convenient location such as a private home, where compactness is a prime requisite. The 75 bells may, of course, be of relatively large size permitting the use of the apparatus in large halls and auditoriums where a large volume of sound is desirable, since the diaphragm from the closed resonator may be 80 sufficiently elastic to produce the appropriate sound waves in a comparatively large bell.

While certain novel features of the invention have been shown and described and are pointed out in the annexed claims, it will 90 be understood that various omissions, substitutions and changes in the forms and details of the device illustrated and in its operation may be made by those skilled in the art without departing from the spirit of the 95 invention.

What is claimed is:

1. In an acoustic device, a tube closed at one end and having an opening at the other end, said opening having a flaring horn applied in communication therewith, and means in said tube adjacent said opening for generating sound waves.

2. In an acoustic device, a tube closed at one end and having an opening in the side wall at the other end, a diaphragm in the wall of said tube opposite said opening, and a source of sound waves in operative relationship to said diaphragm.

3. In an acoustic device, a tube closed at one end and having an opening in the side wall at the other end, said opening having a flaring horn applied in communication therewith, means in the wall of said tube opposite said opening for generating sound waves.

4. In an acoustic device, a tube closed at one end and having an opening in the side wall at the other end, said opening having a flaring horn applied in communication with said opening, means in the side walls of said tube adjacent said opening for generating sound waves.

Signed at New York, in the county of New York and State of New York, this 20 day of May, A. D. 1927.

MILLER REESE HUTCHISON.
